CLAIM

The ornamental design for a portable water filling kit, as shown and described.

DESCRIPTION

FIG. 1 is a side perspective view of a portable water filling kit showing the claimed new design;

FIG. 2 is a top view thereof;

FIG. 3 is a bottom view thereof;

FIG. 4 is a side view thereof;

FIG. 5 is another side view thereof;

FIG. 6 is a rear view thereof;

FIG. 7 is a front view thereof; and,

FIG. 8 is an exploded view thereof.

The broken lines in the figures show portions of the portable water filling kit which form no part of the claimed design. The shade lines in the figures show contour and not surface ornamentation.

1 Claim, 6 Drawing Sheets
